ION PRODUCING MECHANISM (CHARGE CUPS)

William M. Brobeck, Berkeley, Calif., assignor to the United States of America as represented by the United States Atomic Energy Commission

Application February 21, 1946, Serial No. 649,402

3 Claims. (Cl. 250—41.9)

The invention relates to means for ionizing material, particularly material normally in a solid, pulverulent, or granular form, and is particularly concerned with such a mechanism in which the period of operation of the structure is interrupted from time to time for the renewal of material to be ionized. More especially, the invention relates to a calutron of the type shown in U.S. Patent No. 2,709,222, issued May 24, 1955 to Ernest O. Lawrence. In Figures 3 to 5 of the Lawrence application, there is disclosed a particular form of calutron with which one embodiment of the present invention is particularly concerned.

In the operation of a calutron mechanism, it was the practice prior to this invention to provide a block or structure having a chamber therein into which material to be ionized was introduced prior to each run or cycle of operation of the structure. The charge-containing chamber communicated with other chambers leading to other portions of the apparatus, so that there was some difficulty in confining the charge material to the desired locale within the charge chamber. Customarily, the material utilized was in pulverulent or granular condition, and with a careful control of the size of the granules it was possible to handle the charge reasonably well; however, the mentioned procedure was not always convenient and was not sufficiently adaptable to flexible usage. Furthermore, it was observed that the charge material was not always uniformly heated throughout its mass, giving rise to fluctuations in the evolution of vapor or gas for ionization.

In view of the foregoing circumstances, it is therefore an object of my invention to provide a means for more effectively confining a charge material in a calutron.

Another object of my invention is to provide means for facilitating the ready cleaning of a calutron ionization mechanism and the restoration thereof to condition for prompt reoperation.

An additional object of my invention is to provide means for more uniformly distributing the heat to a charge in a calutron.

An additional object of my invention is to provide means for securely holding in position charge containers in a calutron without seriously interfering with their ready removal when desired.

Other objects, together with the foregoing, will appear from the following description, wherein I have described a preferred form of my invention. This form of the invention is also illustrated in the accompanying drawings, in which:

Figure 1 is a fragmentary view of a calutron mechanism, there being shown in section a calutron tank having situated therein a calutron source unit, portions being shown in side elevation and portions being broken away to disclose the interior construction of the mechanism.

Fig. 2 is an exploded, isometric view of the charge chamber and its immediate environment, some portions being disclosed in cross section to illustrate clearly the interior arrangement of the calutron ionization or source mechanism.

2

In order to review briefly the construction of a calutron, disclosed in full in the above-identified Lawrence application, it is pointed out that a calutron is inclusive of an ion source unit, generally designated 6, disposed in the evacuated interior 7 of a tank defined by a side wall 8, a top wall 9, and a bottom wall 11. The tank is situated in a magnetic field established between an upper pole piece 12 and a lower pole piece 13 of an electromagnet.

The source block 6 is electrically insulated from the tank wall 8 and is supported at the end of a mounting stem 14, extending through an aperture 16 in the wall 8 of the tank and carried by a mounting and adjusting mechanism 17. This latter mechanism forms no part of the present invention, and is therefore not described herein in detail. The mechanism 17 is in turn supported on a framework 18 fastened to an electrical insulator 19, itself secured to the tank wall 8 by an appropriate fastening mechanism 21.

As more particularly disclosed in Fig. 2, the inner end 20 of the stem 14 is connected to the source block 6 by thermal insulators 23, as the block 6 itself is preferably fabricated of a thermally conducting material such as a metal, for example copper. Within the block 6 is disposed an electrical heating coil 24, supplied with energy 25 by a lead 26 passing through the insulator 19 to an exterior source of energy. Adjacent the heater 24, in thermally conducting relationship therewith, is a gas distribution chamber 27, constituted by a cavity within the block 6 and having an outlet passage 28 to the interior of the tank 7.

Closing the upper end of the heater cavity 24 and the upper end of the gas distribution cavity 27 is a cover plate 29, secured by fastenings 31 and incorporating a support for a pair of filament leads 32 and 33. The leads extend 35 through the insulator 19 to a source of energy and terminate in grips 34 and 36 holding a filament 37 over an aperture 38 in the plate 29 and in registry with the passage 28. A securing block 41 holds the filament leads 32 and 33 in position, while the enclosure of the filament is 40 completed by a cap plate 42, removably positioned by fasteners (not shown) operating through cap plate apertures 43.

For supplying the gas distribution chamber 27 with a vapor or gas to be subsequently ionized, the block 6 is 45 provided with a pair of cavities 46 and 47, each of cylindrical form and extending almost but not quite entirely through the metal of the block, so that heat from the source 24 is conducted to the walls of each of the cavities 46 and 47. The cavities communicate with the chamber 50 27 through outlet apertures 48 and 49, respectively, so that gas flow from both chambers 46 and 47 to chamber 27 is readily effected. The two chambers 46 and 47 are simultaneously closed by a cover plate 51, preferably held removably in position on the block 6 by fastenings 55 (not shown) operating through apertures, such as 52, in the top plate 51 and in the block 6.

In especial accordance with my invention, each of the chambers 46 and 47 is in part occupied by a charge cup 54 and 55. Each of the cups 54 and 55 is a cylindrical receptacle, preferably fabricated of a good thermal conductor, such as metal, and is disposed removably within its respective cavity, but preferably with a close thermal contact between the conducting wall of the cup and the defining wall of the chamber holding it. The axial extent 65 of the cup is preferably such that the cup stops just short of the associated outlet aperture 48 or 49. The material of the cups, although thermally conducting, is inert to the charge contained therein so that despite protracted use, no interaction occurs. This permits the material of the block 6, if desired, to be made of material that might itself be affected by the solid or granular charge.

In order still better to transmit heat to the contained

charge, each of the cups is provided with a central stem 57, of thermally conducting material effective to conduct heat from the bottom 58 of the cup into the central portion of the contained charge. An additional function is performed by the central stem 57, in that when the cover plate 51 is removed the stem presents a useful projection for engagement with a removing tool.

In accordance with this invention, it is possible, after the plate 51 is removed, to remove the remains of spent charge from a source block 6 and promptly to introduce new loaded charge cups so that a subsequent run can quickly be initiated. Furthermore, the heat is uniformly and evenly distributed to the charge, both from the outside walls and from the center stem of the cup. The charge cups in no wise obstruct the outlet openings, although they do confine the charge to the appropriate chambers. Finally, the charge cups are themselves confined by the removable cover.

What is claimed is:

1. A calutron comprising thermally conducting means forming a charge chamber, a thermally conducting charge holding cup adapted to be removably disposed within said chamber with the walls of said cup in thermally conducting relationship with said chamber-forming means, and a central thermally conducting stem incorporated within said cup for conducting heat to the central portion of a charge contained within said cup.

2. A calutron ion source comprising a source block formed of thermally conducting material and having a

plurality of chambers formed therein, heating means disposed within one of said chambers for supplying heat to said source block, and a charge container removably disposed within another of said chambers in thermally conducting relationship to said source block, said charge container having a heat conducting element centrally disposed therein in contact with a wall thereof whereby the interior of said charge container is uniformly heated.

3. An ion source for a calutron comprising a source block formed of a thermally conducting material, a heating chamber within said source block, an electrical heater disposed within said heating chamber and heating said source block, an arc chamber within said source block and communicating with the exterior thereof, means establishing an arc within said arc chamber to ionize gas fed therein, a charge chamber within said source block communicating with said arc chamber, and a charge cup within said charge chamber in contact with the walls thereof and adapted to contain a charge material which is thereby vaporized by the heat conducted thereto through the charge cup from the source block to flow in gaseous form into said arc chamber to be ionized by the arc therein.
